UNITED STATES PATENT OFFICE

ADOLPH STARR, OF CALUMET CITY, ILLINOIS, ASSIGNOR TO THE SUPERHEATER COMPANY, OF NEW YORK, N. Y.

FEED-WATER HEATER

Application filed February 3, 1928. Serial No. 251,579.

This invention relates to feed-water heaters of the so-called "closed type" and has particular reference to a structure of this type for locomotive use.

5 The object of the invention is to provide a better structure of this kind and for this purpose than has been available heretofore.

The invention is illustrated in the drawings filed herewith, in which Fig. 1 shows 10 a vertical longitudinal section of a feed-water heater according to my invention; Fig. 2 is a view of the device looking at it from below; Fig. 3 is an end view from the left end of Fig. 1; Fig. 4 is a section on line 4—4 15 of Fig. 1, and Fig. 5 is a section on line 5—5 of Fig. 1, the casing being omitted.

Feed-water heaters of the type with which I am herein concerned are intended for the purpose of preheating water which is to 20 be fed to a boiler, for example the boiler of a locomotive, this preheating being done by means of exhaust steam coming from the engine. The heating steam and the water to be heated are not permitted to mingle. The 25 former is on the outside of a set of pipes through the interior of which the water is carried.

The casing 1 has one end, indicated by the reference numeral 2, permanently closed. 30 The other end is provided with a flange 3 to which the tube sheet 4 is secured by means of bolts or studs 5. The tube sheet has a plurality of tube holes arranged as described a little further on, in which the ends of the 35 tubes 6 are secured. As is clearly shown in Fig. 1, the tubes each comprise two straight, parallel lengths and a curved portion 7 joining them. The curved portions 7 are of increasing sizes from the center out and the 40 units or elements in any one plane are nested. In practice the tube units are arranged in vertical planes. The number of units or elements in the various planes are not the same. For example, the innermost tier 7^a on each side of 45 the center comprises five units. The next four tiers outward from the center on each side comprise four units; the next two comprise three; the next tier comprises two, while the last one marked 7^b has only one unit.

50 Against the tube sheet 4 is secured, in a

manner to be described further on, a header 9. This header has four compartments, two of which 9^a and 9^b are quarters of a complete circle, the third of them 9^c being half of a circle. The walls of these three chambers 55 make tight joints with the tube sheet 4, as for example at 10, Fig. 1.

The quarter header 9^a has a connection 8^a, while the quarter header 9^b has a connection 8^b. One of these is to be used as the inlet for 60 the water and the other for the outlet. It will depend upon circumstances which is to be used for inlet and which for outlet. If 8^a is the inlet for the water supplied by the pump, the water will first be delivered to chamber 9^a. 65 From this it will flow through those tubes 6 connecting with it and will by them be delivered into the chamber 9^c. This chamber will carry the water across to the other side and deliver it to those elements whose further ends communicate with the chamber 9^b. 70 The water will thus reach the outlet 8^b.

The exhaust steam which is to heat the water on its course through the heater is delivered into the casing 1 through the two connections 11—11. This steam will condense 75 in heating the water, and the condensate is carried away through the connection 12.

One of the features of my invention is the means I use for securing the chambers or 80 headers 9^a, 9^b, and 9^c to the tube plate. The half section or header 9^c has a semi-circular flange 9^d around its outer circumference, and a straight flange 9^e along its diametrical side. The two quarter sections each have the curved 85 flanges 9^f—9^g extending around a quarter of a circle and the radial straight flanges 9^g—9^h. As will be clear from Fig. 4, two of the radial edges of the sections 9^a and 9^b are in contact with each other and the other two abut against 90 the diametrical flange 9^e. The circumferential flange thus formed is secured to the tube sheet 4 by means of studs and nuts 13. On the abutting straight flanges are laid the clamping pieces 14. Each of these is secured 95 to the tube sheet 4 by means of studs 15—15 which extend through the clamps and flanges, the holes through the flanges being so located that half lies in each flange.

The square piece 32 presses against the cen- 100

tral portion of the flange 9^e and against the inner corners of the radial flanges of the sections 9^a and 9^b, and is held in place by the stud 33, extending through the piece 32 and through a hole which is half in flange 9^e and one-fourth in each of the corners of the other flanges.

By means of this arrangement it is possible to remove either of the quarter sections or the half section without disturbing any joint except that of the piece to be removed.

The straight sides of the sections 9^a, 9^b, 9^c abut against clamping pieces 14—14 and their tendency to bulge under internal pressure is thus largely counteracted. Similarly, any tendency of the arcuate outer sides to bulge is counteracted by the annular raised strip 4^a, against which the edges of these walls abut.

It will be noted that the quarter sections 9^a and 9^b are interchangeable, and this is very convenient in practice because the piping for the water is sometimes from below as in the form illustrated and sometimes at right angles to this direction.

25 To support the ends of the tubular units at the closed end of the heater I have devised the arrangement next to be described. Such support becomes necessary as the total length of these units may be considerable.

30 The support consists in a plate 20 whose general form appears clearly in Fig. 5. It is a sheet of metal generally circular in outline with spaces 16—16 cut away in its circumference and the intervening pieces 17—17 left to bear against the shell. The sheet is perforated to accommodate the tubes 6, these perforations being slightly larger than the tubes so that the sheet can be slid along the entire group of tubes. It is held in position

40 by means of four spaces 18—18. There may of course be some other number of these spacers if it is thought necessary. These spacers are threaded at one end 19 and screwed into the tube sheet 4. Their further ends are also threaded and extend through holes in the sheet 20 and carry the nuts 21.

45 The fit between these openings and rods is quite loose so that the movement of the sheet on the tubes referred to above is not interfered with. The spacers or distance pieces 18 are slotted adjacent to the sheet 20, as indicated at 21, and into these slots are put the keys 22.

50 The supporting sheet 20 will thus be held firmly in place and will keep the tubes 6 from sagging or breaking off. When it is desired to remove a tube from the interior of the bundle (the casing having been removed), it is not necessary to cut out the tubes lying 55 in the same plane outside of it. All that is necessary is to back off the nuts 21 far enough so that the keys 22 can be taken out, after which the sheet 20 can be slid along the nest of tubes until it is adjacent to the tube sheet 60

65 4. The outer tubes can then be sprung apart

far enough to pull out the injured tube after its ends have been cut at the tube sheet, and to put in the substitute tube for it.

The large central opening 30 and the openings 31—31 in the support 20 are for the two-fold purpose of making the sheet lighter and of giving the steam freer access to all parts of the tubes.

I claim:

1. An apparatus of the class described, a casing open at one end, a tube-sheet closing the open end, a plurality of tubes secured to the tube sheet and extending into the casing, a support within the casing at the closed end for the tubes, said support resting on the bottom of the casing and having perforations through which the tubes extend, and spacing bars normally keeping the support in position, the support perforations being large enough so the support can be slipped along the tubes to the tube sheet when the connections between the support and spacing bars are released.

2. In apparatus of the class described, a cylindrical casing open at one end, a tube sheet closing the open end, a plurality of U-shaped tubular units extending into the shell and each having its two ends secured to the tube sheet, a perforated support within the casing at its closed end for the units, the tubes extending through the perforations, spacing bars each secured by one end to the tube sheet and having its second end extending through the support, and readily detachable means to lock the second ends of the spacing bars to the support, the spacing bars and the straight portions of the units being parallel whereby, when the support is unlocked from the bars, it may be slid to the tube sheet.

3. Apparatus according to claim 2 the U-shaped units being arranged in parallel planes each plane containing a plurality of nested units.

4. In apparatus of the class described the combination of a circular tube sheet, a plurality of sector-shaped hollow headers applied to the tube sheet, each header having radial flanges, the flanges of adjoining headers being in contact, bars each engaging adjoining flanges, and a row of studs along the line of contact between each pair of flanges and extending through the bar into the tube sheet.

ADOLPH STARR.
